US00D872955S

(12) **United States Design Patent** (10) **Patent No.:** **US D872,955 S**
(45) **Date of Patent:** **** Jan. 14, 2020**

(54) **SURFACE CLEANING HEAD**(71) Applicant: **SHARKNINJA OPERATING LLC**,
Needham, MA (US)(72) Inventors: **Jason B. Thorne**, Dover, MA (US);
Yao Ming, Suzhou (CN); **Daniel R. Der Marderosian**, Westwood, MA (US); **Daniel Meyer**, Boston, MA (US); **Patrick Cleary**, Allston, MA (US); **Gordon Howes**, Suzhou (CN); **David Wu**, Needham, MA (US); **Nancy Gao Wenxiu**, Suzhou (CN)(73) Assignee: **SharkNinja Operating LLC**,
Needham, MA (US)(**) Term: **15 Years**(21) Appl. No.: **29/690,973**(22) Filed: **May 13, 2019****Related U.S. Application Data**

(60) Division of application No. 29/601,158, filed on Apr. 19, 2017, now Pat. No. Des. 849,345, which is a continuation-in-part of application No. 15/331,045, filed on Oct. 21, 2016.

Primary Examiner — Ruth McInroy(74) *Attorney, Agent, or Firm* — Grossman Tucker
Perreault & Pfleger, PLLC**(57) CLAIM**

We claim the ornamental design for surface cleaning head, as shown and described.

DESCRIPTION

FIG. 1 is a front view of a surface cleaning head showing our new design;

FIG. 2 is a bottom view thereof;

FIG. 3 is a right side bottom perspective view thereof; and,

FIG. 4 is a left side bottom perspective view thereof.
The broken lines are included for the purpose of illustrating the unclaimed portions of the article and form no part of the claim.**1 Claim, 4 Drawing Sheets**# US D872,955 S
